DIE ASSEMBLY

Angel R. Rivera, Detroit, Mich.

Application July 25, 1957, Serial No. 674,217

3 Claims. (Cl. 164—58)

My invention pertains to a die, including a main body portion and an operative member such as a shearing blade which may be adjustably moved with respect thereto by means of a mechanism contained in said main body portion. The object of my invention is to provide means whereby the operative member of the die may be adjusted with respect to said body portion by a single operation, without the necessity of removing the die as a whole from the position it may occupy upon supporting means therefore, and without the necessity of disassembling the elements of which the die is composed.

A further object of the invention is to provide a die of such structure that the operative member such as the blade may be easily removed from the main body portion without the necessity of moving the main body portion from the place upon which the body is mounted. This refers to such events as, for instance, when the blade has to be ground to render it more efficient.

I shall now describe my improvement with reference to the accompanying drawings in which:

Fig. 1 is a perspective view of the die, including the main body portion and the movable operative element thereof;

Fig. 2 is a top elevational view of the die;

Fig. 3 is a rear elevational view thereof;

Fig. 4 is a sectional view on line 4—4 of Fig. 3;

Fig. 5 is a sectional view on line 5—5 of Fig. 3;

Fig. 6 is a front elevational view of the main body portion of the die.

Similar numerals refer to similar parts throughout the several views.

The main body of the die, generally identified by numeral 10, has the form of a rectangular block defined by flat surfaces, including a flat rear surface 11, a flat top surface 12, and a flat front surface 13. The block 10 is provided with a bore 14 extending through the block from the rear surface into the front portion thereof where it is expanded radially into a cylindrical aperture 15, opening outwardly. The bore 14 is located centrally within said block 10, being at a point intermediate the sides of the block and intermediate the top and bottom thereof as best shown in Fig. 1.

Disposed within the aperture 15 is a pinion 16, the pinion being axially mounted upon a shaft 17 which extends rearwardly from the pinion into said bore 14. The rear portion of the shaft within the bore is provided with an annular groove 18, and includes an end portion 19 of reduced diameter. The last named portion 19 of the shaft serves as an axial support of a worm gear 20, the latter including a cylindrical hub portion 21 which is secured to the shaft by means of a diametrically disposed pin 22.

The worm gear 19 is in mesh with a worm 23, disposed in a vertical bore 23a, the worm being provided with a head 24 in an expanded portion 25 of the bore. Said head 24 is of the socket type for application of a wrench for the operation of the worm.

To prevent displacement of the worm, the latter is

2

made with an annular groove 26 for engagement with a retaining pin 27. The pin 27 is located in a bore 28 extending parallel to the bore 14 in the upper portion of the block shown in Figs. 1 and 2. Similarly, to prevent displacement of the shaft 17 from the bore 14, a set screw 29 is threaded into a vertical bore 30, the screw terminating at its lower end with a smooth tip 31 which projects into the above said groove 18 in the shaft 17, while a socket type screw 32 is threaded into the bore 30 against the set screw therebelow.

The front portion of the block contains two horizontal slideways, one 33, being located in the upper portion of the block, the other 34, in the lower portion thereof. Each of the slideways has the form of an oblong groove open towards the front of the block and extending from one end of the block to the other. The groove is defined by a flat horizontal bottom or lower surface, a flat horizontal top surface, and by a vertical back surface 38, which is set at an angle to the flat vertical front surface of the block. As a result thereof, the slideway along its length is of gradually increasing depth as measured with relation to said front surface of the block. However, while the depth of one slideway increases in one direction of its length, the depth of the other slideway increases in the opposite direction of its length.

This increase in the depth of the slideway 34, is shown in Fig. 5 in which the block is shown in horizontal section disclosing the shape of the slideway as seen from above. It will be noted on reference to Fig. 6, that the lower surface of the upper slideway intersects the circular aperture 15 in the front portion of the block, and that similarly the upper surface of the lower slideway intersects said aperture from below. Located in each slideway is an oblong rack 35 in mesh with the pinion 16. Each rack is of the same thickness all along its length, but of a gradually increasing width so that when viewed in plan elevation it has the shape of a wedge. This is shown in Fig. 5, which discloses the rack in the lower slideway 34. When the rack is within a respective slideway, in what

40 may be considered its normal or initial position, one side 36 of the rack is flush with the outer surface 13 of the block while the opposite side 37 is set at an angle to said surface, being in a sliding abutment along its length with the back wall 38 of the respective slideway. By reason of the angularly set back wall 38, and by reason of the wedge-shape of the rack, the rack, if moved endwise in the slideway in the direction of its decreasing depth, will be forced outwardly beyond the front face 13 of the block.

50 It will be noted that, as shown in Figs. 5 and 6, each wedge 35 is shorter than the length of the slideway in which it is located, and that at its narrow end, the wedge includes a portion 35a which is devoid of teeth, this being necessary to allow movement of the wedge crosswise over the end of the respective bolt 44 projecting from the block and threaded into the blade 46.

55 Drilled into the front portion of the block, between the two slideways 33 and 34, are two bores 39, these being spaced from each other along an imaginary horizontal line, each of the bores serving to support a horizontally disposed guiding pin 40 which projects outwardly of the block. In addition the block contains two holes 41 extending parallel to the bore 14, one being located on one side thereof in the upper portion of the block, the other to the other side of the bore 14 in the lower portion of said block. One of the holes intersects in part, the upper slideway 33, while the other hole intersects in part, the lower slideway 34. Each of the holes is threaded, but includes an unthreaded rear portion 41a of expanded diameter, each of the holes serving for reception of a bolt 44 having a socket type head 45. The bolts are adapted to project from within the block beyond the front

60 65 70

surface thereof for connection with an operative member of the die marked 46. This is a thick vertical blade defined in its upper portion by a face 47 slanting upwardly and outwardly from the block, and a flat narrow top 48 extending horizontally, for intersection with the flat front face 49 of the blade along a straight horizontal line which defines the shearing edge 50 of the blade.

For the purpose of being secured to the block by means of said bolts, 44, the blade has two transverse bores 51 which are threaded and which are spaced from each other so as to be brought into register with the holes 41. Furthermore, the blade is provided with the bores 52 for reception of two guiding pins 40. The position of the blade when connected to the block by said bolts is such that the top portion 48 of the blade with the cutting edge 50 is at a level above the top surface of the block 10 as shown in Fig. 1. As the block 10 is to be held in place upon a supporting base or platform, it is provided with two vertical holes 53 for employment of screws 56, by means of which the block may be drawn in tight against said supporting base, while two other vertical holes 54 open at the top and extending downwardly through the block, serve to receive dowel pins 55 to hold the block against any horizontal movement upon said supporting base, which is not shown.

I shall now describe the operation of the mechanism disclosed herein.

For the purpose of the operative use of the die, the block 10 is mounted on a stationary support and is held in place by screws 56, described above. The blade 46 is held tightly against the front of the block by bolts 44. The stock to be cut, such as a stack of sheet paper, marked 60, is supported from below on a vertical movable table, which is not shown, and is adapted to be brought with said supporting table, under pressure downwardly so that the stack of paper is brought from above against the shearing edge 50 of the blade. As this is a common practice, any further description of the shearing operation does not appear to be needed.

In time, the cutting edge becomes worn and dull, whereupon it becomes necessary to have the blade disconnected from the block and to have its front face ground sufficiently to again secure an efficient cutting edge. The removal of the blade from the block is an easy problem, as all that is needed is to unscrew the bolts 44 from the threaded bores 51 within the blade. However, when the blade is again secured to the block by the same bolts, it becomes necessary to move the blade forwardly from the position held by said blade before the grinding operation. This forward movement or adjustment is called for to compensate for the decrease in the thickness of the blade because of the grinding operation. The adjustment is effected first by partly unscrewing said bolts 44 from the bores 51 within the blade. Thereupon, by means of a wrench applied to the head 24 of the worm 23, a rotary movement is imparted to the worm gear 20. As the gear rotates about its axis, it imparts a similar rotary action to the pinion 16, by means of the shaft 17. The pinion being in mesh with the racks 35 will cause said racks to move in opposite direction from each other. As shown in Fig. 5, the rack disclosed therein, is adapted to be shifted longitudinally in the direction of the arrow marked "r." As the rack is shifted in said direction, which is the direction of the decreasing depth of the lower slideway, the opposite side of the rack will gradually project outwardly of the slideway, bearing against the blade and pushing it outwardly to a new position, shown in dotted lines in Figs. 4 and 5. Obviously the upper rack moving in the opposite direction, duplicates the action of the first described rack in pushing the blade away from the block. After the blade has been sufficiently moved forwardly of the block, the bolts 44 are used to draw the blade into a tight contact with the front sides of the racks to hold the blade against movement.

It will be understood that the structure shown by me

may be modified without departing from the inventive principle disclosed herein, and that said mechanism may be employed for adjustment or movement of other elements than a blade.

5 After having described my invention, I wish to present the following claims:

1. A die including a stationary block defined by a flat front surface having two oblong grooves disposed horizontally in a spaced parallel relation to each other, each groove being defined by a flat bottom, flat top, and a back wall set obliquely to said front face of the block, one groove having a decreasing depth in one direction of the length of the groove, while the other groove has a decreasing depth in the opposite direction of its length, a wedge shaped rack in each groove, each rack having one side disposed parallel to the front face of the block while its other side bears slidingly against the back wall of the respective groove, the teeth of one rack facing the teeth of the other rack, the block being provided with a bore running at right angle to the front face of the block and terminating with a radially expanded cavity in the front portion thereof, the cavity intersecting both grooves, a shaft disposed within said bore, a pinion mounted on one end of the shaft for rotation therewith, said pinion being located within said cavity and being in mesh with both racks, a worm gear axially mounted on the other end of the shaft, a worm disposed within a vertical bore in the block, and being in engagement with the worm gear, the worm serving as a means for the operation of the pinion, the block being further provided with a plurality of holes extending parallel to the shaft, a flat blade disposed parallel to the front face of the block and including a cutting edge, the blade containing a plurality of transverse, threaded bores, and a bolt passing through each hole in the block and threaded into a respective bore in the blade, to draw the blade towards the block.

2. A die including a stationary rectangular block having a flat front face, the block being provided with a circular cavity extending at right angle from the said front face rearwardly, and with two horizontal grooves disposed parallel to each other, one intersecting the cavity at the top, the other intersecting the cavity at the bottom, each of the grooves being defined in part by a back wall, one groove gradually increasing in depth in one direction of its length, the other groove gradually increasing in depth in the opposite direction of its length, a pinion located within said cavity for rotation therein, a wedge shaped rack in each groove, one side of the wedge being its front side, extending parallel to the front face of the block, the other, or the rear side of the wedge, being in abutment along its length with the back wall of the groove in which the rack is located, the teeth of one rack being in mesh with the pinion from below, the teeth of the other rack being in mesh with the pinion from above, a shaft extending axially from the pinion rearwardly of the front face of the block, and gear means within the block for the operation of the shaft and the pinion, the block being further provided with a plurality of holes extending parallel to the shaft, a flat blade disposed parallel to the front face of the block and including a cutting edge, the blade containing a plurality of transverse, threaded bores, and a bolt passing through each hole in the block and threaded into a respective bore in the blade, to draw the blade towards the block.

3. A die including a main body portion which is stationary, the body portion including a flat front face provided with two parallel slideways open towards the front face, each slideway being in part defined by a back wall set on an angle to the front face of the body portion, one slideway decreasing in depth in one direction of its length, the other slideway decreasing in depth in the opposite direction of its length, a wedge like rack disposed lengthwise in each slideway, one side of each rack being parallel to said front face of the main body portion, the other

side being in a sliding abutment with the back wall of the respective slideway, the teeth of one rack facing the teeth of the other rack, a pinion disposed within the main body portion crosswise to the racks in a space therebetween, and being in mesh with both of them, a shaft axially extending from the pinion rearwardly of the front face of the main body portion, a gear wheel mounted on the shaft for rotation therewith, and a worm in mesh with said gear wheel for the operation thereof, the body portion of the die being provided with a plurality of holes extending through said body portion parallel to the shaft, a flat blade disposed in front of the body portion parallel to its flat face, the blade including a cutting edge and

containing a plurality of transverse, threaded bores for register with the last named holes in the body of the die, and a bolt in each hole, the bolt being threaded at one end for engagement with the threaded bores in the blade to draw the blade towards said body portion.
